(57) **CLAIM**

The ornamental design for a portable recharger device, as shown and described.

DESCRIPTION

FIG. 1 is a top front left perspective view of a portable recharger device showing the new design;

FIG. 2 is a bottom rear right perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.

The broken lines in the Figures show portions of the portable recharger device that form no part of the claimed design.
